(57) **CLAIM**

The ornamental design for a hair styling iron, as shown and described.

DESCRIPTION

FIG. 1 is a top perspective view of a first embodiment of the present new design of a hair styling iron;

FIG. 2 is a top view of the hair styling iron of FIG. 1; FIG. 3 is a bottom view of the hair styling iron of FIG. 1; FIG. 4 is a left side view of the hair styling iron of FIG. 1 with a right side view being a mirror image of this left side view;

FIG. 5 is a front view of the hair styling iron of FIG. 1; FIG. 6 is a rear view of the hair styling iron of FIG. 1; FIG. 7 is a top perspective view of the hair styling iron of FIG. 1 in an opened position;

FIG. 8 is a top perspective view of a second embodiment of the present new design of a hair styling iron;

FIG. 9 is a top view of the hair styling iron of FIG. 8; FIG. 10 is a bottom view of the hair styling iron of FIG. 8; FIG. 11 is a left side view of the hair styling iron of FIG. 8 with a right side view being a mirror image of this left side view;

FIG. 12 is a front view of the hair styling iron of FIG. 8; FIG. 13 is a rear view of the hair styling iron of FIG. 8; FIG. 14 is a top perspective view of the hair styling iron of FIG. 8 in an opened position;

FIG. 15 is a top perspective view of third embodiment of the present new design of a hair styling iron;

FIG. 16 is a top view of the hair styling iron of FIG. 15; FIG. 17 is a bottom view of the hair styling iron of FIG. 15; FIG. 18 is a left side view of the hair styling iron of FIG. 15 with a right side view being a mirror image of this left side view;

FIG. 19 is a front view of the hair styling iron of FIG. 15; FIG. 20 is a rear view of the hair styling iron of FIG. 15; and, FIG. 21 is a top perspective view of the hair styling iron of FIG. 15 in an opened position.

The broken line environmental showing is for illustrative purposes only and forms no part of the claimed design.
